UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

UNCOUPLING DEVICE.

Application filed November 2, 1926. Serial No. 145,781.

My invention relates to an uncoupling device employed for the purpose of causing the locking mechanism of a car coupler to assume the positions required to unlock and 5 open the coupler knuckle.

At the present time car couplers almost universally embody means for preventing the locking block by which uncoupling rotation of the knuckle is restrained from accidentally moving to unlocked position as the 10 result of shocks and vibrations incident to the movement of the train. This function of preventing accidental unlocking of the coupler is usually performed by the lifter for 15 moving the lock to unlocked position. Where the speed of the train is moderate the commonly employed means for retaining the lock in locked position is usually satisfactory, but it is the object of my invention to provide 20 means for preventing the coupler lock from accidentally moving to unlocked position by so constructing the uncoupling device for actuating the locking mechanism of a car coupler that the parts of said device will be 25 restrained from accidentally assuming a position corresponding to that which they are required to occupy when the coupler is unlocked.

The principal feature of the invention 30 consists in forming an uncoupling lever for actuating the locking mechanism of a car coupler as an outer rotatable member combined with an inner rotatable member, the two members being capable of independent 35 rotary movement and the outer member being adapted to actuate the inner so as to move the latter to uncoupling position; and in associating therewith a bracket rigidly mounted on the car body and affording 40 spaced pivotal supports for the said rotatable members and also providing a lug or projection adapted to interlock with the inner lever member so as to prevent accidental uncoupling rotation of the latter, the 45 said inner member having at its outer end an opening forming a downwardly facing shoulder and an inclined face or wall converging downwardly toward the pivotal bearing for the said inner lever member, 50 the said shoulder being adapted to lap over the said locking lug so as to enable the latter to support the outer end of the inner lever member in elevated position, and the inclined face or wall of the opening being

adapted to cooperate with the pivotal bearing for the inner lever member to thereby prevent the shoulder from moving into overlapped relation with the locking lug so long as the inner end of the inner lever member is approximately in normal coupled position. 55

Other features of the invention, pertaining to advantageous combinations of parts and structural details will hereinafter appear and be pointed out in the claims. 60

In the drawings illustrating a preferred embodiment of the invention,—

Figure 1 is a plan view of an uncoupling device embodying the invention showing its relation to the car and car coupler, the parts 70 being in locked relation.

Figure 2 is an elevational view of the construction illustrated in Fig. 1, the parts being in locked position.

Figure 3 is an end elevational view showing the relation of the parts when the coupler lock is in lock-set position. 75

Figure 4 is an elevational view showing the parts in the positions they occupy when the uncoupling device is actuated for throwing the knuckle open, this being also the position which the parts assume in the act of setting the lock in lock-set position before the downward force applied to the outer end of the outer lever arm is released. 80

Figure 5 is a detail elevational view of a portion of the mechanism, the parts being in locked position and a portion of the outer lever member being broken away.

Figure 6 is a detail sectional view on the 90 line 6—6, Fig. 1.

The car coupler 1 illustrated in the drawings for the purpose of disclosing the relation of the improved uncoupling device thereto is of the well known standard D 95 type having a lock lifter 2 which extends upwardly through the top of the coupler head so as to be operatively connected to the uncoupling device. The locking block serves normally to prevent an uncoupling 100 rotation of the coupler knuckle is moved to unlocked position by this lifter which also cooperates with the coupler head to prevent the locking block from accidentally jarring upward to unlocked position.

The coupler locking mechanism is actuated by an uncoupling device formed as an uncoupling lever consisting of an outer mem-

ber 3 and an inner member 4. The inner end 5 of the member 4 is preferably of cylindrical form and projects through the usual eye at the upper end of the lock lifter 5 2 a sufficient distance to accommodate the movements of the coupler. The outer arm 6 of the lever member 3 is designed to be depressed either by the hand or the foot so as to effect an uncoupling operation of the 10 parts.

Rigidly mounted upon the car body is a bracket 7 on which the transversely extending uncoupling lever is fulcrumed. The lever members overlap at the bracket and 15 the inner arm 8 of the outer member 3 is bent so as to extend under the inner lever member 4, thereby enabling an uncoupling movement of the latter to be effected by a corresponding movement of the outer lever 20 member 3.

The fulcrum bracket 7 is provided with a pivotal bearing for the outer lever member 3 preferably formed as a cylindrical stud 9, the lever member being retained in assembled relation therewith by means of a nut 10 and washer 11. The bracket also affords a pivotal bearing for the inner lever member 4, said bearing being conveniently constituted by a downwardly projecting lug 12 30 whose lower end is circularly curved on a center or axis which is spaced from that of the pivot lug 9 upon which the outer member 3 is mounted. In addition to these pivotal bearing portions for the respective lever members, the bracket 7 is formed with a locking lug or projection 13 which is adapted to cooperate with the inner lever member 4 to prevent accidental rotation of the latter to uncoupling position. The fulcrum bracket may also conveniently be provided with an upwardly extending lug 14 40 and a downwardly extending lug 15 for preventing inward movement of the lever member 4 with respect to the bracket; and for 45 the purpose of limiting the movement of the outer lever member 3 in an uncoupling direction the fulcrum bracket may also embody a forwardly projecting lug or stop portion 16 which extends beneath the outer arm 50 3 of the uncoupling lever in spaced relation to the pivotal axis of the latter.

The outer end of the inner lever member 4 is fashioned with an opening or recess 17 into which portions of the fulcrum bracket 55 7 extend. The upper portion of this recess is narrowed or constricted, as at 18, so as to conform to the locking lug 13 and adjacent part of the fulcrum bracket. Below the portion normally occupied by the locking 60 lug 13 the opening 17 is widened on the side toward the coupler so as to provide a shoulder 19 beneath which the upper end of the said lug 13 extends when, as shown in Fig. 4, the outer lever member 3 is actuated to effect an uncoupling operation of the 65

mechanism. Adjacent to and below the shoulder 19, the face or wall 20 of the opening is inclined downwardly so as to slope toward the projection 12 of the bracket forming the pivotal bearing for the inner 70 lever member 4. The lower wall 21 of the opening is rounded so as to permit pivotal movement of the lever 4 when the latter bears against its pivot projection 12 of the bracket. 75

When the trainman presses down on the outer end of the outer uncoupling lever member 3 its inner arm 8 presses upwardly on the under side of the inner member 4, thereby causing the outer end of the latter to move directly upward until the locking lug 13 of the fulcrum bracket passes out of the constricted portion of the opening 19 in the last mentioned lever member. Thereafter the continued uncoupling rotation of 80 the outer member 3 brings the outer end of the inner member 4 into engagement with the rounded lower end of the pivotal projection 12 of the fulcrum bracket and induces an unlocking rotation of the inner lever member 4 around this point as a pivotal center. This rotary movement of the inner member 4 causes its shoulder 19 to move into overlapping relation with the upper end of the locking lug 13 of the bracket. 85 If the knuckle of the coupler is not free to rotate to open position when the uncoupling device is actuated, the release of the downward pressure upon the outer member 3 permits the parts to assume the lock-set relation illustrated in Fig. 3, the shoulder 19 of the member 4 resting upon the upper end of the locking lug 13 so as to support the outer end of the inner lever member in elevated position. If the knuckle is free to 90 rotate outwardly when the outer uncoupling member 3 is actuated, the latter causes the inner lever member 4 to perform the extended uncoupling rotation necessary to move the coupler a sufficient distance to effect the 95 knuckle opening operation of the coupler mechanism. When, by the subsequent operation of the coupler, the locking mechanism thereof reassumes normal or locked position, the inner lever member 4 rotates so 100 that the shoulder 19 thereof is disengaged from the lug 13, thus permitting the parts 105 of the mechanism to reassume normal locked position. 110 115

It will be perceived that the lug 13 of the fulcrum bracket by cooperating with the inner lever member 4 serves to prevent the latter from accidentally performing an unlocking operation. It is also to be noted that while the shoulder 19 of the inner lever member laps the locking lug 13 of the fulcrum bracket when said lever member is at rest in lock set position, this lap cannot exist unless the inner end of the inner member 4 is raised as shown in Fig. 3. As long as the 120 125 130

inner end of the inner lever member 4 remains anywhere near its normal locked position, as shown in Fig. 2, any accidental upward movement of the member 4 causes its 5 inclined surface 20 to contact with the projection 12 on the fulcrum casting, and the cooperation of these two parts prevents any chance overlapping of the lug 13 and shoulder 19 which would allow the outer end of 10 the inner lever member 4 to hang on the fulcrum or pivot casting should it be accidentally jarred upward. The outer end of the inner lever member 4 is always free to drop back to locked relation except when it 15 is in lock set position.

I claim:—

1. An uncoupling device for actuating the locking mechanism of a car coupler, said device involving an uncoupling lever comprising an operating arm and an operated arm, means for pivotally mounting the operating arm on the car body, said operating arm being adapted to engage the operated arm to effect an uncoupling movement of the latter, and means fixed with respect to the pivotal axis of the operating lever adapted to engage said operated lever to prevent the latter from accidentally moving to uncoupling position, said operating lever upon an uncoupling rotation being adapted to shift said operated lever so as to release it from the control of said last named means. 25
2. An uncoupling device for actuating the locking mechanism of a car coupler, said device involving an uncoupling lever having an outer rotatable member and an inner rotatable member, said members being relatively movable and rotatable on spaced pivotal axes, and means mounted on the car body forming spaced pivotal supports for said rotatable members, said inner member 30
3. An uncoupling device for actuating the locking mechanism of a car coupler, said device involving an uncoupling lever comprising an outer rotatable member and an inner rotatable member, said outer member being pivotally mounted on the car body and said inner member being movable independently of said outer member and being adapted to be actuated by the latter, and a bracket carried by the car providing pivotal bearings for said lever members and a locking lug for preventing said inner member from accidentally moving to uncoupling position, said inner member being provided adjacent said bracket with a recess for receiving said lug and pivotal bearings, said recess being shouldered to permit the outer end of said inner member to be supported on said lug, and a wall of said recess adjacent said shoulder being inclined downwardly toward the pivotal bearing for said inner lever member, whereby said shoulder is prevented from 35 moving into overlapped relation with said lug when the outer end of said inner member accidentally moves upward while its inner end is substantially in coupled position. 40

In testimony whereof I affix my signature.

WILLIAM KELSO.
